J. B. Andrews,
Saw Buck.

No. 93,034.

Patented July 27, 1869.

United States Patent Office.

J. B. ANDREWS, OF BRIDGETON CENTRE, MAINE.

Letters Patent No. 93,034, dated July 27, 1869.

IMPROVEMENT IN SAW-HORSE.

The Schedule referred to in these Letters Patent and making part of the same.

To all whom it may concern:

Be it known that I, J. B. ANDREWS, of Bridgeton Centre, in the county of Cumberland, and State of Maine, have invented a new and useful Improved Saw-Horse; and I hereby declare the following to be a full, clear, and exact description thereof, which will enable others to make and use my invention, reference being had to the accompanying drawings, forming part of this specification, in which—

A is a side sectional elevation.

B, a detail of the holder for the saw-blade.

C, a side view of one of same.

D, the device to hold the saw when not in use.

I am aware that a patent has been granted for a saw-horse, having a device to hold the wood while being sawed, but my invention is different in appliances from that; and consists of a device to hold the wood securely, and of another to receive the saw as soon as a stick is cut.

a is a cross-bar, stretching between the bottoms of two of the common cross-legs of a saw-horse, and turning, when desired, on a pivot, b, set into each leg.

c is another bar, similarly placed at the bottom of the two other cross-legs, and having the pivot d.

To d is attached the pedal e, made so as to be pressed down with the foot, but when released, always pressed upwardly, by the V-spring f, attached to the under side of the bar c.

Attached to the pedal e is the arm h, pivoted at i and j.

Set into the cross-bar c, midway between the two pairs of cross-legs of the horse, is the upright toothed arm k.

Now, as the foot is pressed upon the pedal e, this arm k is drawn down toward the cross-bar m of the horse, so as to seize and hold a piece of wood placed on the same to be sawed.

When the pressure of the foot is withdrawn from e, k will again resume the position shown in the drawing.

This arm k is in the centre of the horse, half way between the legs. The advantage of this is, that if the wood is caught by the saw, it does not lift directly up on the foot placed on the pedal e, as would be the case if k has a vertical movement up and down, as in patent 31,605, May 5, 1861, before referred to, but the strain comes, in this case, on the bar c, to which k is attached, because k moves off from and on the wood laterally. This makes it easier to hold the wood to be sawed, and is what I claim for my improvement in holding the wood.

n are teeth, to aid in confining the wood.

o is a catch, into which the saw can be placed as the person sawing, for instance, bends to place a fresh piece of wood on the horse, or to adjust the one already on, after a piece has been sawed off from it. This catch o is placed at the top end of one of the legs.

p are rests for a saw-blade, into which it can be placed to be filed or sharpened. These are placed on the outside of two of the cross-legs of the horse, on the same end thereof, so that the saw is placed across such two legs when it is to be sharpened or otherwise repaired.

The patent No. 31,605, March 5, 1861, to which I have referred above, gives a vertical movement to the hook to hold the wood. I do not claim a hook, or the movement of any spring to operate the pedal.

I do not claim the application of a pedal, with hook and spring, attached to a saw-horse, as in patent of George Ives, No. 31,605, March 5, 1861. Neither do I claim jaws provided with teeth, and a sliding frame between the jaws, and a treadle to operate the device; patent of E. Whittemore, No. 38,351, April 28, 1863. Neither do I claim the jaw-frames, each composed of two bars, united together by cross-bars at their lower ends, and one frame within the other, to form a folding horse; patent of E. Whittemore, February 9, 1864. No. 41,560.

Operating the clamping-device by pedals is not new, and I do not claim that, for it is common to the above-mentioned patents; but my application relates to the arrangement of arm k, rod h, and pedal e, so that the wood, when lifted up by the saw, does not draw upward directly on the pedal, and thus require the exertion of strength to keep the wood in position. The wood is, when lifted by the saw, drawn vertically, but the movement of k is off laterally, so that the disturbance of the wood by the saw has but little tendency to throw up k; but

What I do claim as my invention, and desire to secure by Letters Patent, is—

The arrangement of pedal e, rod h, V-spring f, and toothed arm k, on a saw-horse, in connection with the fixed teeth n and rest o, for the purpose of easily holding the saw and wood to be sawed, the whole operating as herein set forth.

J. B. ANDREWS.
